UNITED STATES PATENT OFFICE.

FRANK J. HALL, OF PHILADELPHIA, PENNSYLVANIA.

WOVEN PILE FABRIC.

No. 874,677.

Specification of Letters Patent.

Patented Dec. 24, 1907.

Application filed July 3, 1906. Serial No. 324,559.

To all whom it may concern:

Be it known that I, FRANK J. HALL, a citizen of the United States, residing at the city of Philadelphia, in the county of Philadelphia and State of Pennsylvania, have invented certain new and useful Improvements in Woven Pile Fabrics, of which the following is a specification.

My invention has relation to a woven pile fabric, in which first, the pile tufts or threads are securely bound to form the face of the fabric by warp-threads; and second, in which the pile tufts or threads are conducted around the warp threads prior to the introduction of the weft-threads and the latter arranged so as to be directly beneath the pile tufts or threads.

The principal objects of my invention are first, to produce a woven pile fabric in which the backing may be formed of any desired number of warp and weft-threads to form a plain, patterned or figured weave or a reinforced or stiffened weave to give body to the fabric; second, to produce a woven pile fabric in which the pile tufts or threads constituting the face of the fabric are tied by warp-threads; third, to produce a woven pile fabric in which the pile tufts or threads rest directly over weft-threads to permit the pile tufts or threads to lie side by side and hence to form a dense pile or tuft face; fourth, to form the pile face by introducing a single or series of threads around warp threads in each shed in the weave of the fabric; and fifth, to introduce the pile tufts or threads around warp-threads only, prior to introducing the weft-thread or threads in the production of the fabric so as to permit of the tying of the pile tufts or threads by the warp-threads only, and of being bound by the weft-threads.

The nature and scope of my present invention will be more fully understood from the following description, taken in connection with the accompanying drawings forming part hereof, in which

Figure 1 is a view illustrating partly in section and partly in elevation a pile fabric in which the pile tufts or threads are tied to the warp-threads in each shed or weave and the shed or weave formed of two sets of weft-threads, separated from each other by a stuffer warp-thread and binder warp-threads, and also illustrating the manner of forming the sheds by the binder and stuffer warp-threads, the means for conducting the pile tufts or threads around the warp-threads

and a lay for beating up the pile tufts or threads and weft-threads in the weave of the fabric, all embodying main features of my said invention; and Fig. 2 is a view similar to Fig. 1, but illustrating the manner of producing a pile fabric, with the stuffer warp-thread omitted.

Referring to the drawings with reference to Fig. 1, *a* and *a'* represent two sets of weft-threads; and *b*, a stuffer warp-thread floating between the weft-threads and separating the same from each other. The weft-threads *a* and *a'*, and the stuffer warp-thread *b*, are bound together by two binder warp-threads *c* and *c'*, in such manner that in each shed two weft-threads are bound to the stuffer warp-thread *b*, and pile tufts or threads *d*, are bound to a warp-thread passing over the upper weft thread *a*. The loops *d'*, of the pile tufts or threads forming the face tufts of pile of the fabric rest directly over a weft-thread *a*, and by the pressure exerted by the weft-thread the loops *d'*, of pile tufts or threads are held firmly in engagement with the respective binder warp-threads *c* or *c'*, to thereby lock the pile threads to the warp-thread and to prevent disengagement of the same from the warp-thread by pulling or otherwise. The pile tufts or threads *d*, thus secured by the respective warp-threads form the face of the fabric, and owing to their introduction into each shed of the weave there will be the same number of pile tufts or threads in each set, as there are weft-threads *a* or *a'*, in the shed, and when the fabric is beaten up in a well known manner by the lay *e*, the pile tufts or threads *d*, will be brought close together and will rest side by side forming thereby a pile or tuft face of decided density, without objectionable grinning of the backing therethrough. In the introduction of the stuffer warp-thread *b*, with the additional weft-threads *a'*, the backing formed is strong and stiff for giving decided body to the fabric. Grinning of the pile loops *d'*, of the fabric as is the case in fabrics in which the pile threads are bound alone by the weft-threads is entirely obviated by tying the pile tufts or threads by the warp-threads. This grinning of the pile threads or tufts is also prevented when the stuffer warp-thread *b*, and the additional weft-threads *a'*, are dispensed with, as shown in Fig. 2, as also in this instance the pile tufts or threads *d*, will be covered by the weft-threads *a*, and therefore not visible at the face of the fabric.

Although a plain weave is formed by employing one set of weft-threads *a*, and two binder warp-threads *c* and *c'*, as shown in Fig. 2, yet the pile tufts or threads *d*, will be likewise securely tied and bound by the warp-threads to the face of the fabric and firmly held in position over the weft-threads *a*, in each set of the weave throughout the sheds of the fabric, as is the case in the production of the fabric of Fig. 1. Aside from being of less stiffness as to the body thereof, the woven pile tuft fabric of Fig. 2 does not differ from the fabric illustrated in Fig. 1. In order to place the pile tufts or threads *d*, directly over the weft-threads *a*, in each shed throughout the fabric, the binder warp-thread *c*, and stuffer warp-thread *b*, are depressed as shown in Fig. 1, and the pile tufts or threads *d*, are first conducted around the warp-threads *c'*, and moved forwards to the place of weaving by mechanism to be herein-after more fully described. After the pile tufts or threads *d* have been shifted to their proper position, the weft-threads *a* are shot into the shed so formed directly beneath the loop *d'*, of the pile tufts or threads *d*, as indicated in dotted lines in Fig. 1, after which the stuffer warp-thread *b*, is raised and the second weft-thread *a'*, and pile tufts or threads *d*, are now beaten up by the lay *e*, in the usual well known manner and brought into alinement with each other. For the formation of the succeeding shed, both the binder warp-threads *c'*, and the stuffer warp-thread *b*, are lowered, while at the same time, the binder warp-thread *c*, is raised into the position occupied by the thread *c'*, in Fig. 1, and so on in regular sequence throughout in the fabrication of the woven pile fabric. By the beating up of the weft and pile tufts or threads, the pile tufts or threads *d*, are brought very close together, and rest side by side forming thereby in the fabric produced by the weft-threads *a* and *a'*, and warp-threads *b*, *c* and *c'*, a pile tuft surface of great density and in which each of the pile tufts or threads *d* is bound on the face of the fabric by the binder warp-threads *c* and *c'*, and each held above a weft-thread *a*. The pile tufts or threads *d*, thus securely held between the warp-threads and weft-thread will be locked against removal or pulling out. The thread employed for forming the pile or tufts of the fabric may consist either of a series of single threads or tufts, as shown in Figs. 1 and 2, or may be formed of a series of thin fluffy threads *ad libitum*, bound or tied by the warp-threads in separate sheds throughout, as hereinbefore described.

The preferred mechanism for inserting the pile tufts or threads *d*, around the binder warp-threads occupying the raised position, is as follows:—As shown in Fig. 1, each of the pile tufts or threads *d*, is conducted through a feeding finger *f*, consisting of a flat metal

tube *f'*, which is curved upwardly as at *f''*, and is bent sidewise at the free end thereof, as at *f'''*. The feeding fingers *f*, are supported by a bar *h*, which is raised and lowered and partially turned in a vertical plane and is shifted forwards in a raised position, in a horizontal plane, by any suitable mechanism, not shown. Each of the fingers *f*, is provided at its curved portion *f'*, with a knife-like projection *f''*, which, when the fingers are depressed, aid in the proper insertion of the feeding fingers *f*, between the warp-threads. The pile tufts or threads *d*, which are supplied to each of the feeding fingers *f*, by a spool or other means of support, not shown, project a certain distance from the free ends *f'''*, and are conducted around a warp-thread in the following manner: When the fingers *f*, are lowered by the bar *h*, the same will pass between the warp-threads, in the present instance, the warp-threads *c'*, during which downward movement the free ends *f'''*, thereof, owing to their location sidewise of the shanks *f'*, of the fingers *f*, will move the warp-threads sidewise. As soon as the fingers *f*, are brought with their free ends *f'''*, below the warp-threads *c'*, the same released from the pressure exerted thereon by these ends will return to their normal straight position and the projecting ends *d''*, of the pile tufts or threads *d*, which were first conveyed downward at one side of the warp-threads *c'*, will be moved over the same, and upwards on the other side of the warp-threads, as shown in Fig. 1. Thus by a straight downward movement of the feeding fingers *f*, each of these fingers conduct pile tufts or threads *d*, around a warp-thread *c* or *c'*, and hence the turning of the feeding fingers from straight to oblique positions and the movement of the warp-threads by a specially arranged comb to conduct pile threads around the warp-threads, as is the case in the U. S. Patent No. 723,342, dated March 24th, 1903, is effectively overcome. The ends *d''*, of the pile tufts or threads *d*, projecting from the fingers *f*, above the warp-threads *c'*, are now engaged by clamping bars *i* and *i'*, supported and actuated by means, not shown, and are held in position by the same. The fingers *f*, by means of the bar *h*, are now brought out of engagement with the warp-threads *c'*, by a combined turning and upward movement in the same plane, in which the fingers descended, by which movements the free ends *f'''*, of the fingers *f*, are moved from one side of the warp-threads to the other side thereof, and by being brought into the first position shown by dotted lines in Fig. 1, conduct the pile tufts or threads *d*, which are held at their ends *d''*, by the clamping bars *i* and *i'*, in a reverse direction to that in which the same were inserted, around the warp-threads. The fingers *f*, and the clamping bars *i* and *i'*, are now moved into the second position shown

by dotted lines in Fig. 1, and by this movement the pile tufts or threads *d*, are brought to the point for weaving the fabric. After the pile tufts or threads have thus been properly placed on the warp-threads *c*, knives *k* and *k'*, supported and actuated by means, not shown, are moved forward to cut the pile threads in a line with the projecting end *d*³ of the same, thus leaving a sufficient portion 10 projecting from the free ends *f*³ of the fingers *f*, to form a portion of the succeeding pile loops and permit of their engagement by the clamping bars *i* and *i'*. A weft thread *a*, is now introduced into the shed directly below the pile loop *d*, as shown by the dotted lines in Fig. 1, and after closing the shed and beating up the pile tufts or threads *d*, and weft-threads, the pile tufts or threads inserted in a manner such as hereinbefore described, will be securely held and bound by the warp-threads. By such arrangement each finger *f*, is adapted to introduce pile threads differing in color from adjoining pile threads and hence the number of colors that 25 may be employed to produce a pattern or design in a woven pile fabric, is unlimited. Moreover, by the particular outline and shape of the feeding fingers *f*, there may be used as many fingers as there are warp-threads, and hence the pile tufts or threads 30 will not only rest side by side in a longitudinal plane in the fabric, but also in a plane transversely thereto.

Having thus described the nature and objects of my invention, what I claim as new and desire to secure by Letters Patent is:—

1. In a woven pile fabric, two binder

warp-threads, weft-threads, and interwoven separately cut pile tufts or threads bound by the warp-threads occupying a raised position in each shed and said separately cut pile tufts or threads tied to said warp-threads. 40

2. In a woven pile fabric, two binder warp-threads, a stuffer warp-thread, and separately cut pile tufts or threads bound by a warp-thread occupying a raised position in each shed, weft-threads introduced above and below the stuffer warp-thread, the upper weft-thread located beneath the cut pile tufts or threads and said separately 45 cut pile tufts or threads tied to the warp-threads to form a cut pile face in the fabric. 50

3. In a woven pile fabric, binder warp-threads, a stuffer warp-thread, pile tufts or threads bound by the warp-thread occupying the raised position in each shed, weft-threads introduced above and below the stuffer warp-thread, the upper weft-thread introduced below the cut pile tufts or threads, said stuffer warp-thread and weft-threads bound together by said binder warp-threads to form the backing of the fabric, and said separately cut pile tufts or threads tied or bound in each shed by the binder warp-threads to the backing to form a 60 dense cut pile tuft face. 65

In witness whereof, I have hereunto set my signature in the presence of two subscribing witnesses.
